The ornamental design for a broadhead with expandable blades and resilient O-ring, as shown and described.

DESCRIPTION

FIG. 1 is a perspective view of a broadhead with expandable blades and resilient O-ring showing of my new design;

FIG. 2 is a top plan view thereof;

FIG. 3 is a side elevational view of the left side thereof;

FIG. 4 is a side view of the right side thereof;

FIG. 5 is a bottom plan view thereof;

FIG. 6 is a front elevational view thereof;

FIG. 7 is a rear elevational view thereof;

FIG. 8 is a perspective view showing the resilient O-ring removed and the blades open;

FIG. 9 is a side view of the right side of FIG. 8;

FIG. 10 is a side view of the left side of FIG. 8;

FIG. 11 is a bottom plan view of FIG. 8;

FIG. 12 is a top plan view of FIG. 8;

FIG. 13 is a front elevational view of FIG. 8; and,

FIG. 14 is a rear elevational view of FIG. 8.
